UNITED STATES PATENT OFFICE.

HENRY M. LANE, OF CINCINNATI, OHIO.

STOOL FOR INGOT-MOLDS.

1,286,660.

Specification of Letters Patent.

Patented Dec. 3, 1918.

Application filed March 22, 1917. Serial No. 156,625.

To all whom it may concern:

Be it known that I, HENRY M. LANE, a citizen of the United States, residing at Cincinnati, in the county of Hamilton and 5 State of Ohio, have invented certain new and useful Improvements in Stools for Ingot-Molds; and I do hereby declare the following to be a full, clear, and exact description of the invention, such as will enable 10 others skilled in the art to which it appertains to make and use the same.

My present invention relates to an improved form of stool for ingot molds used in casting steel and the like, and the object 15 of the invention is to supply a form of stool whereby the formation of fins on the ingots may be certainly avoided, without resort to fire clay dams or other devices tending to affect injuriously the quality of the metal.

20 Steel ingots are generally cast in heavy iron molds which are set, generally in pairs, upon suitable stools or bases, whereby the lower end of each mold is closed, so as to confine the molten metal when poured.

25 When the bottom face of the mold and the top of the stool are left rough, a certain portion of the metal exudes and forms a projecting fin around the bottom of the ingot. This has two principal disadvantages. First, the fin end which goes into 30 the reheating furnace is injurious to the refractory lining of the furnace; and secondly, the bottom end of the ingot, carrying the fin, is placed in the rolls first, and when 35 rolled down a lamination is produced which is very objectionable.

To remedy this difficulty, the chipping off of the fins has been resorted to, which involves waste of labor and time. It has also 40 been proposed to machine the bottom faces of the molds to a smooth flat surface, but this is not sufficient where the top face of the stool is not also a smooth flat surface. The machining of this top surface of the 45 stool has hitherto been impracticable or extremely awkward of accomplishment for the following reasons.

As the ingot molds are extremely heavy, sometimes weighing thousands of pounds, 50 they are lowered to the tops of the stools by overhead cranes; and, as it is not economical to provide laborers to guide each to its place, it has been customary to provide upstanding beveled or sloping-faced guiding 55 flanges at the four corners, by the aid of which the man operating the crane can lower

each mold to its place without extra assistance. These upstanding guides interfere with convenient machining of the upper or supporting face of the stool. 60

It is the object of my present invention to provide a stool of such a form and construction that the entire supporting surface of a stool for one or more molds can be machined to a true smooth surface by a single 65 operation.

For this purpose I employ corner guides for the molds only at the outer corners and make their inner faces concentric with the center of the stool plate. These corner 70 guides are sufficient where only one mold is to be supported. Where two molds are supported, the inner sides of the molds are guided by a central boss having sloping guiding sides also concentric with the center 75 of the plate. By this means I have only to mount the whole plate in a boring mill so as to revolve it around the center in question, and am thus able to smooth the supporting 80 surface and cut all the inclined guiding surfaces in one operation.

The invention may be embodied in a variety of forms, some of which are shown in the accompanying figures of drawing, wherein in Figure 1 is a top view of one of my improved stools as used for a pair of molds, Fig. 2 is a side elevation of the same, Fig. 3 shows a modified form as used for three ingot molds, and Fig. 4 shows a modification as used for four molds. 85

In the form shown in Fig. 1, the base 10 is provided with a central guiding boss or projection 11, having conical faces 12 and 13 on its opposite sides, and at the two ends of said base upstanding guiding flanges 14, 90 15 and 16, 17 are provided at the four corners. These flanges, instead of being conformed to the shape of the ingot molds (indicated in dotted lines in Fig. 1) as has hitherto been the practice, are curved circularly with the center of the boss 11 as their center, and they are provided with inwardly facing conical guiding surfaces 18, 19 and 20, 21; also cut on radii from the same center. This construction makes it 100 possible successfully to cut a smooth upper face on the base 10 and smooth conical surfaces on the boss and flanges in one operation in a boring mill.

The general principle of the invention can 110 be applied to a three-mold stool in the manner shown in Fig. 3; or to a four-mold stool

in the manner shown in Fig. 4. It will be observed that all of these forms have a common characteristic, in that the guiding means provided for each ingot mold comprises one or more concave projections on the outer side of the mold and a convex projection on the inner side of the same. By the "inner side" is meant that nearer the center, and by the "outer side" is meant that 10 away from the center of the stool.

In Fig. 3, the outer molds (indicated in dotted lines) are guided between the concave projections 22, 23, 24, 25, and the convex projections 26 and 27. These latter are, of course, concave toward the central mold, and serve as guides for it. All of the guiding projections are cut concentrically around the center of the stool, thereby securing the benefits above described with reference to 20 the mode of cutting and smoothing the surfaces. It will be seen that some of the guides are continuous across the full width of the stool, while others are separated by a space. These differences show that it is 25 indifferent to my invention whether or not the guides are carried across the stool.

Fig. 4 presents a combination of the two forms shown in Figs. 1 and 3, and the two inner molds of the total of four are guided 30 in the same manner as are the two in Fig. 1,

while the outer molds in Figs. 3 and 4 are guided by identical means.

What I claim is:—

1. A stool for ingot molds having a flat face provided with outer and inner guiding 35 projections, presenting to the molds concentric guiding surfaces, respectively concave and convex, whereby the face of the stool and said guiding faces may be shaped in a boring mill or the like in one operation. 40

2. A stool for ingot molds having a flat face and outer and concentric inner guiding projections thereon arranged so as to admit and guide the ingot molds between them, substantially as described. 45

3. A stool for ingot molds having a flat face, an inner boss having convex sides and outer concave guides having guiding surfaces concentric with said convex sides of said boss. 50

4. A stool for ingot molds having a flat face, a central guiding boss with concave sides, and two sets of inwardly concave guides having guiding surfaces concentric with the convex surfaces of said boss, the 55 intermediate guides also having convex guiding surfaces concentric with the other guiding surfaces.

In testimony whereof I affix my signature.

HENRY M. LANE.
